UNITED STATES PATENT OFFICE

150,657

DESIGN FOR A LETTER OPENER OR SIMILAR ARTICLE

Davison M. Richardson, Mobile, Ala.

Application May 6, 1947, Serial No. 138,843

Term of patent 14 years

(Cl. D74—1)

To all whom it may concern:

Be it known that Davison M. Richardson, a citizen of the United States, residing at Mobile, in the county of Mobile and State of Alabama, has invented a new, original, and ornamental Design for a Letter Opener or Similar Article, of which the following is a specification, reference being had to the accompanying drawing, forming part thereof, wherein—

Fig. 1 is a side elevational view of a letter opener or similar article, showing my new design; and

Fig. 2 is an edge elevational view of the same.

I claim:

The ornamental design for a letter opener or similar article, as shown.

DAVISON M. RICHARDSON.
